UNITED STATES PATENT OFFICE.

PATRICK M. SCANLAN, OF BROOKLYN, NEW YORK.

PUMP.

1,314,707.

Specification of Letters Patent. Patented Sept. 2, 1919.

Application filed March 8, 1918. Serial No. 221,126.

To all whom it may concern:

Be it known that I, PATRICK M. SCANLAN, a citizen of the United States, and residing at Brooklyn, in the county of Kings and 5 State of New York, have invented certain new and useful Improvements in Pumps, of which the following is a specification, such as will enable those skilled in the art to which it appertains to make and use the 10 same.

This invention relates to pumps and more particularly to what are known as air pumps or devices of this class designed for use in inflating pneumatic tires; and the object 15 thereof is to provide an air pump which is simple in construction, effective in operation and which may be more conveniently and easily operated than other devices of this class, and with the exertion of a minimum 20 of effort or power; a further object being to provide an improved air pump which may, in addition to being operated for the purpose specified, be also used for the purpose of pumping or compressing air in most of 25 the relations or for most of the purposes for which such devices are usually employed; and with these and other objects in view the invention consists in an air pump constructed and operated as hereinafter 30 claimed.

The invention described and claimed herein is an improvement on that described and claimed in a prior application filed by me January 24, 1918, Serial No. 213,511, and 35 which is fully disclosed in the following specification, of which the accompanying drawing forms a part, in which the separate parts of my improvement are designated by suitable reference characters in each of the 40 views, and in which:—

Figure 1 a side view of my improved pump showing the same in its folded position;

Fig. 2 a view at right angles to that shown 45 in Fig. 1 and showing the pump in position for use or with the folded parts thereof extended;

Fig. 3 a partial section on the line 3—3 of Fig. 2 and on an enlarged scale;

Fig. 4 a plan view of a handle member 50 which I employ;

Fig. 5 a section on the line 5—5 of Fig. 3; and, Fig. 6 an enlarged detail sectional view of a valve device shown in Fig. 3.

In the practice of my invention, I provide 55 a base *a* which is approximately rectangular in form and comprises a top member *a*² and opposite depending sides *a*³. Secured centrally of the base *a* and between the sides *a*³ thereof is a block *b* provided with a longitudinal bore *b*², the open end of which is closed by a plug *b*³. The block *b* is held in place by a tubular piston rod *c*, the lower end of which is reduced and threaded into said block as clearly shown at *c*² in Fig. 3, 65 and placed between the block *b* and base *a* is a packing sheet *b*⁴ which seals the connection of the piston rod *c* with the block *b*, as will be readily understood, and as will be noted in Fig. 3 said piston rod communicates with the bore *b*² in said block. 70

Connected with the upper end of the piston rod *c* is a piston *d* of the form and construction shown in the application above referred to, and which is mounted on a reduced end *c*³ of the rod *c* and held in such position by a tubular lock nut *d*², and mounted in the reduced end *c*³ of the rod *c* is a valve mechanism *d*³ of any desired form and construction and which may be similar 80 to that shown in said prior application and adapted to control the intake and exhaust of air through a port or passage *c*⁴ in the piston rod *c* inwardly of the piston *d* as clearly shown in Fig. 3. 85

The detail construction of the valve mechanism *d*³ is shown in Fig. 6 of the drawing and consists of a flexible sleeve *d*⁴ adapted to normally close the port or passage *c*⁴. Placed within the sleeve *d*⁴ is a 90 valve casing *d*⁵ within which is a tensionally operated valve *d*⁶ adapted to control the passage of air into the tubular rod *c* and through a sleeve plug *d*⁷ secured in the lock nut *d*².

The piston *d* is movable longitudinally through a cylinder *e* closed at its upper and lower ends by caps *e*² and *e*³ between which and the ends of the cylinder *e* are placed two fibrous disks *e*⁴ and *e*⁵. The disk *e*⁵ is 100 cut out as shown at *e*⁶ in line with, or adjacent to an aperture *e*⁷ in each of the caps *e*² and *e*³, while the disks *e*⁴ are cut out as shown at *e*⁸ in Fig. 5 to form tongue or valve members *e*⁹ which are movable 105 through the apertures *e*⁶ in the disk *e*⁵ and adapted to open and close the apertures *e*⁷ in the caps *e*² and *e*³, and this construction

of the caps e^2 and e^3 is clearly shown in Figs. 3 and 5 of the drawing.

The cylinder e is inclosed in an oblong frame member f which is U-shaped in form or provided with an integral head member f^2 , and the opposite end of which is closed by a transverse plate f^3 secured to the open end of the frame, and the sides of the frame f are provided between the center thereof and the upper end of said frame with oppositely arranged elongated apertures f^4 , five of which are shown in Fig. 2. The top f^2 of the frame f is provided with a depressed portion f^5 which is adapted to enter a similar depressed portion e^{10} in the central top portion of the cap e^2 , as clearly shown in Fig. 3, and this construction serves to center the cylinder e within the frame f and hold the cap end e^2 thereof against displacement in said frame as will be readily understood.

The lower end of the cylinder e is connected with the plate f^3 at the bottom of the frame f by a sleeve g adjustably mounted in the plate f^3 and provided at its outer end with a nut-shaped head g^2 , and the inner end of said sleeve is adapted to bear on the face of the cap e^3 , as clearly shown in Fig. 3, and a supplemental inner sleeve h is threaded into the inner end of the sleeve g and is provided with a shoulder h^2 adapted to bear on the disks e^4 and e^5 to seal the connection of the cylinder, or the cap e^3 thereof, at this point, and said supplemental sleeve h is provided with an enlarged nut-shaped head h^3 on the inner end thereof whereby the same may be manipulated.

Another supplemental sleeve i is adjustably mounted in the outer end of the sleeve g and is adapted to operate in connection with a packing i^2 placed in the sleeve g between the supplemental sleeves h and i and serves to hold said packing in firm position to seal the connection of the piston rod c with the cylinder e in the operation of said cylinder, as hereinafter described.

A coupling plug j is connected with the top a^2 of the base a at one side thereof and the end j^2 thereof communicates with the bore b^2 in the block b , as clearly shown in Fig. 3, while a flexible hose j^3 is connected with the projecting end of said coupling, and in Figs. 1 and 2, I have shown oppositely arranged foot pieces k which are yoke-shaped in form as clearly indicated in Fig. 1, and are pivoted to the opposite sides a^3 of the base a as shown at k^2 inwardly of said side, and these foot pieces are adapted to normally swing into the position shown in full lines in Fig. 1 and into the position indicated in dotted lines in Fig. 2, but may be lowered into the position shown in full lines in Fig. 2 when in use, and the feet of the operator are placed thereon in the operation of the pump as hereinafter described.

I also employ a handle member m composed of two hand pieces m^2 and m^3 connected by opposite frame members m^4 provided with inwardly directed members m^5 , having reduced ends m^6 . The reduced ends m^6 of the inwardly directed members m^5 are adapted to operate in connection with the apertures f^4 in the sides of the frame f as clearly indicated in Figs. 2 and 3, and in order to hold the handle member m in position against displacement I employ lock members n pivoted to the side members of the frame f , as shown at n^2 , and comprising inner rectangular U-shaped bodies n^3 which are adapted to operate in connection with the opposite side walls of the cylinder e when in the position shown in Fig. 1 to spring the sides of the frame f outwardly, which operation binds the handle member m in connection with said frame, as will be readily understood. The lock members n are provided with finger pieces n^4 whereby they may be swung inwardly and outwardly on their pivots at n^2 to permit the attachment and detachment of the handle member.

From the foregoing description the operation of my improved pump will be readily understood when taken in connection with the accompanying drawing and the following statement. The position of the pump as shown in Fig. 1 is the folded position thereof, the handle member m being detached, and when it is desired to use the pump the lock members n are first moved outwardly out of engagement with the sides of the frame f and the foot pieces k are swung downwardly into the position shown in full lines in Fig. 2, after which the handle member m is placed in any of the oppositely arranged apertures f^4 and locked in such position by moving the lock members n back into the position shown in Figs. 1 and 2 to spring the sides of the frame f outwardly, and in manipulating the pump the feet of the operator are placed on the foot pieces k and the handle member m grasped by the hands of the operator and the cylinder e is first raised from the position shown in the drawing on the piston rod c and piston d , in which operation the air in the cylinder e is forced out through the aperture c^4 through the tubular piston rod c , the bore b^2 in the block b , through the coupling j and out through the flexible tube j^3 , and in this operation air is also admitted into the cylinder e above the piston d through the port or passage e^7 in the top cap e^2 controlled by the tongue or valve e^9 . In the downward movement of the cylinder e over the piston rod c and piston d , the air previously admitted into the cylinder e through the port e^7 in the cap e^2 is discharged from said cylinder through the valve device d^3 in the end of the piston rod c through said rod, the bore b^2 in the

block *b*, the coupling *j* and out through the flexible tube *j*⁸, and in this operation air is also admitted into the cylinder *e* below the piston *d* through the port *e*⁷ in the cap *e*⁸ as will be readily understood.

- The connection of the separate parts of my improved pump will be similar to the connection of the separate parts of the pump as shown in said prior application, the piston 10 rod *c* being connected with the base *a* and block *b* mounted therein, the piston *b* connected with the upper end of said rod and the valve mechanism *d*⁹ mounted in said end of the piston rod, it being understood that 15 the frame *f* with the sleeve *g* and supplemental sleeves *h* and *i* are mounted on the rod *c* with the cap *e*⁸ secured in place between the sleeve *g* and supplemental sleeve *h*. The cylinder *e* is then passed over the piston 20 *d* when the cap *e*⁸ is drawn in position adjacent to said piston and the cap *e*² is placed on the upper end of the cylinder *e*, and said cylinder swung into vertical alinement with and within the frame *f*, after which the 25 sleeve *g* is adjusted into the position shown in the drawing to move the cylinder *e* vertically to lock it in engagement with the top *f*² of the frame or to bring the depressed portions *f*⁵ and *e*¹⁰ together, and in this position of the parts the cylinder *e* is held in 30 firm connection with the frame *f*, as will be readily understood. The detachment of the cylinder *e* for cleaning or repairing the separate parts of the pump will be accomplished 35 by loosening the sleeve *g* to bring the cap end *e*² of the cylinder *e* out of engagement with the top *f*² of the frame, and said cylinder may then be removed from the piston rod and piston as will be readily understood.
- 40 The connection of the handle member *m* with the frame *f* is an adjustable one by reason of the apertures *f*⁴, and in this way the position of said handle member may be regulated to suit the operator and it will be noted that the operator in grasping the 45 handpieces *m*² and *m*³ of the handle member *m* will be able to operate the cylinder *e* over the piston or piston rod with more power and with his arms in a more comfortable 50 position than will pump devices of similar class employing the usual transverse handle on the end of the piston rod, in other words, in the operation of my pump the arms of the operator are in their normal position and not 55 in a twisted position as with pumps of the present construction, and by folding the foot pieces *k* into position longitudinally of the frame *f* and cylinder *e*, and by detachably connecting the handle member *m*, my 60 improved pump may be compactly wrapped for shipment or other purposes, and will not take up an unnecessary amount of room; but it will be understood that various changes in and modifications of the details of construction herein shown and described may be

made, within the scope of the appended claims, without departing from the spirit of my invention or sacrificing its advantages.

Having fully described my invention, what I claim as new and desire to secure by 70 Letters Patent, is:—

1. A device of the class described, comprising a base, a piston rod connected with said base, a piston connected with said piston rod, a cylinder mounted on said piston and piston rod and movable longitudinally thereof, a frame inclosing said cylinder and in which said cylinder is detachably mounted, and means connected with said frame for moving said cylinder longitudinally of said piston and piston rod. 75

2. A device of the class described, comprising a base, a piston rod connected with said base, a piston connected with said piston rod, a cylinder mounted on said piston and piston rod and movable longitudinally thereof, a frame inclosing said cylinder and in which said cylinder is detachably mounted, and a handle member adjustably connected with said frame and adapted to operate said cylinder. 85

3. A device of the class described, comprising a base, a piston rod connected with said base, a piston connected with said piston rod, a cylinder mounted on said piston and piston rod and movable longitudinally thereof, a frame inclosing said cylinder and in which said cylinder is detachably mounted, means for locking said cylinder against movement in said frame, means connected 95 with said frame for moving said cylinder longitudinally of said piston and piston rod, and means for admitting air into said cylinder and discharging it from said cylinder through said piston rod and said base. 100

4. A device of the class described, comprising a base, a piston rod connected with said base, a piston connected with said piston rod, a cylinder mounted on said piston and piston rod and movable longitudinally thereof, a frame inclosing said cylinder and in which said cylinder is detachably mounted, means for locking said cylinder against movement in said frame, means connected 110 with said frame for moving said cylinder longitudinally of said piston and piston rod, means at each end of the cylinder for admitting air thereinto in the movement of said cylinder on said piston and piston rod, and means for discharging air from said cylinder through said piston rod and said base. 115

5. A device of the class described, comprising a base, a piston rod connected with said base, a piston connected with said piston rod, a cylinder mounted on said piston and piston rod and movable longitudinally thereof, a frame inclosing said cylinder and in which said cylinder is detachably mounted, means for locking said cylinder against 125 130 135

- movement in said frame, means connected with said frame for moving said cylinder longitudinally of said piston and piston rod, the opposite ends of said cylinder being 5 provided with intake ports or passage controlled by a valve device and the piston end of the piston rod being provided with exhaust ports or passages controlled by a valve mechanism mounted in said piston rod 10 whereby the air admitted into the cylinder through the intake ports or passages in the opposite ends thereof may be discharged through the exhaust ports or passages in the piston rod and through the base with 15 which said piston rod is connected.
6. A device of the class described comprising a base, a tubular piston rod connected with said base, a flexible tube coupling connected with said base and placed in communication with said piston rod through a 20 port or passage in said base, a piston connected with said piston rod, a cylinder mounted on said piston and piston rod and movable longitudinally thereof, said cylinder being provided with end caps adapted to close the same, a frame inclosing said cylinder, means for locking one end of the cylinder against lateral movement in said frame, and means at the other end of said 25 cylinder for moving the same longitudinally of said frame and locking it therein against transverse and lateral movement, and a handle member adjustably connected with said frame and adapted to operate said cylinder on said piston and piston rod.
7. A device of the class described, comprising a base, a tubular piston rod connected with said base, a flexible tube coupling connected with said base and placed in communication with said piston rod through a 30 port or passage in said base, a piston connected with said piston rod, a cylinder mounted on said piston and piston rod and movable longitudinally thereof, said cylinder being provided with end caps adapted to close the same, a frame inclosing said 35

cylinder, means for locking one end of the cylinder against lateral movement in said frame, and means at the other end of said cylinder for moving the same longitudinally of said frame and locking it therein against transverse and lateral movement, and the opposite sides of said frame being provided with a plurality of oppositely arranged apertures, a handle member adapted 50 to be mounted in said apertures and means connected with said side frame members for holding the same in firm connection with said handle member.

8. In a device of the class described, a base, foot pieces movably connected with said base, a pump mechanism connected with said base and involving a frame, a cylinder detachably mounted in said frame, a piston mounted in said cylinder and a tubular piston rod connected with said piston and passing out through one end of the cylinder and connected with said base, means connected with said frame for moving the cylinder longitudinally of said piston and piston rod, and valve devices in said cylinder and said piston rod for admitting air into said cylinder and discharging it therefrom through said tubular piston rod and through said base.

9. In a pump device of the class described, the combination with a pump cylinder mounted on and movable longitudinally of a piston and piston rod, of a frame in which said cylinder is detachably mounted and said frame being provided with means whereby said cylinder may be moved longitudinally of said piston and piston rod.

In testimony that I claim the foregoing as my invention I have signed my name in presence of the subscribing witnesses this 6th day of March, 1918.
